UNITED STATES PATENT OFFICE.

EDWARD G. KRANTZ, OF HIGHLAND, ILLINOIS.

CLUTCH-LOCK FOR AUTOMOBILES.

1,321,216.

Specification of Letters Patent.

Patented Nov. 11, 1919.

Application filed April 5, 1917. Serial No. 160,029.

To all whom it may concern:

Be it known that I, EDWARD G. KRANTZ, a citizen of the United States, residing at Highland, in the county of Madison and State of Illinois, have invented certain new and useful Improvements in Clutch-Locks for Automobiles, of which the following is a specification.

This invention relates to clutch locks and has special adaptation for use on automobiles.

An object of the invention is to provide a locking means for the clutch pedals, whereby the latter will be rendered inoperative when desired, but will be readily accessible to authorized persons.

A further object is to provide a device which is equally applicable to the different types of automobiles and which will in no way interfere with the operator of the vehicle or with the mechanism forming a part of the latter.

The above and other objects and advantages of this invention will be in part described and in part understood from the following description of the present preferred embodiment, the same being illustrated in the accompanying drawings in which:

Figure 1 is a perspective view of a lock constructed in accordance with my invention, illustrating the application thereof.

Fig. 2 is a longitudinal sectional view of the locking device, and

Fig. 3 is a top plan view of the same, showing the closure thereof removed.

In the drawings in order to illustrate the application of my invention, a portion of the floor or foot board 1 of an automobile is shown, with which is associated a clutch pedal 2 of the usual or any desired configuration. The lock generally designated 3 is shown as arranged in close proximity to the clutch pedal 2.

The lock consists of an elongated casing 4, preferably made of metal and equipped with a bar 5 which is secured to the bottom of the casing in any suitable manner. The casing is adapted to be countersunk in the floor 1 and is provided with a flange 6 to which bolts 7 are connected, for securing the casing. The casing is provided with a closure 8 which is hingedly or otherwise mounted on the upper margin of the casing and is provided with a keyway 9. The closure 8 may, of course, be locked in any suitable way

on the casing 4, access being gained thereto for releasing the lock through the keyway 9.

The end of the bar 5, which is adjacent the clutch pedal 2, is turned upwardly at right angles, as indicated at 10, and is provided with an opening through which a bolt 11 is slidably mounted. The bolt 11 is freely movable in the casing 4 and may be projected beyond the latter through an opening 12. The end of the casing therefore acts as a bearing, in conjunction with the right-angled portion of the bar 5, for the locking bolt 11. The inner end of the bolt is equipped with a finger trip piece 13, which is pivotally mounted and has a nose 14 formed thereon which is adapted for engagement in either one of openings 15. In this way the bolt may be locked while in an operative position as shown in Fig. 2, or if desired may be locked when in an inoperative position, by engaging the nose 14 with the opening 15 which is farthest remote from the right-angled end 10 of the bar 5. It is, of course, understood that the bolt 11 is so arranged that it will either lie in the path of the clutch lever or else will pass through an opening in the clutch lever, as shown in Fig. 2.

A metallic strap 16 is transversely arranged over the top of the bolt 11 and secured thereto. The ends of said strap are turned upwardly at right angles and are adapted to abut the opposite walls of the casing 4 to facilitate guiding of the bolts.

In use therefore it will be appreciated that when the operator desires to lock his clutch pedal, the closure 8 of the casing 4 is opened and the operator moves the bolt 11 through the medium of the finger piece 13 into the position shown in Fig. 2. The bolt cannot be retracted in the casing until the finger piece 13 has been raised and consequently when the closure 8 is locked access to the finger piece 13 will be closed with an obvious result.

It will be understood that the above description and accompanying drawings comprehend only the general and preferred embodiment of my invention and that various minor changes in details of construction, proportion and arrangement of parts may be made within the scope of the appended claims without sacrificing any of the advantages of my invention.

I claim:

1. In a device of the character described,

the combination of a casing, a bar fixed within said casing and having openings formed therethrough intermediate its ends, one end of said bar being turned to extend at right angles thereto, said end being provided with an opening formed therethrough, said casing having an opening therein in alignment with the opening of the extended end of said bar, a bolt slideable through the openings thus being held against side swinging movement, and means for holding said bolt in adjusted position.

2. In a device of the character described, the combination of a casing, a bar fixed within said casing and having openings formed therethrough intermediate its ends, said bar being bent adjacent one end to form an angularly extending end portion having an opening extending therethrough, said casing having an opening therethrough in alignment with the opening of said bent end, a bolt slideable through said openings, thus being held against side movement, a finger piece pivotally mounted upon the inner end of said bolt, said finger piece having a nose adapted to fit within one of the openings of said bar to hold the bolt in an adjusted position and a movable closure for said casing engaging said finger piece to hold the same against accidental shifting, whereby the bolt will be held against unauthorized movement.

3. In a device of the character described, the combination of a casing having an open-

ing in one end thereof, a bar fixed within said casing and extending longitudinally thereof, said bar terminating in an upturned apertured end and spaced from said casing, said apertured end and said opening being in alignment with each other, said bar having openings formed therethrough intermediate its ends, a bolt slideable through said first mentioned opening and aperture, thus being held against side movement, a finger piece pivotally mounted upon the inner end of said bolt and having a nose adapted to be received within one of said last mentioned openings of said bar, a movable closure carried upon said casing for engaging said finger piece and holding the same against pivotal movement, whereby said bolt will be held against accidental unauthorized shifting, a strap fixed upon said bolt and extending transversely thereof, said strap having angularly bent ends which are substantially parallel to each other engaging the inner surfaces of said casing, whereby said bolt will be held against accidental rotation, thus being held to properly slide when said nose is released from engagement with said bar.

In testimony whereof I affix my signature in presence of two witnesses.

EDWARD G. KRANTZ.
